ATTORNEY

UNITED STATES PATENT OFFICE.

ALFRED C. HOWARD, OF MOLINE, ILLINOIS, ASSIGNOR TO E. AND T. FAIRBANKS AND COMPANY, OF ST. JOHNSBURY, VERMONT, A CORPORATION OF VERMONT.

WEIGHBEAM.

Application filed October 15, 1924. Serial No. 743,653.

To all whom it may concern:

Be it known that I, ALFRED C. HOWARD, a citizen of the United States, residing at Moline, county of Rock Island, and State 5 of Illinois, have invented certain new and useful Improvements in Weighbeams, fully described and represented in the following specification and the accompanying drawings, forming a part of the same.

10 This invention relates to weigh-beams for use with scales.

It is an object of the invention to provide an improved means for mounting a traveling poise on a weigh-beam whereby the points of 15 suspension of the poise will be unaffected by slight irregularities in beam or poise condition under varying conditions of service.

Another object of the invention is to provide an improved weigh-beam of the character mentioned which is relatively simple in 20 construction and reliable and exact in function under all conditions of service.

Other objects will be in part obvious from the following detailed description and in 25 part pointed out hereinafter.

The invention accordingly consists in the features of construction, combination of elements and arrangements of parts which will be exemplified in the construction herein- 30 after set forth, and the scope of the application of which will be indicated in the following claims.

In the accompanying drawings wherein one embodiment of the invention is dis- 35 closed:

Figure 1 is a side elevation of the improved weigh-beam;

Fig. 2 is a horizontal section through the poise, taken approximately on the line 2—2 40 of Fig. 1;

Fig. 3, is a face view of one of the sections forming the poise, as seen from the line 3—3, of Fig. 2 showing the manner in which the poise is mounted on the beam;

45 Fig. 4 is a vertical transverse section taken on the line 4—4 of Fig. 3, and

Fig. 5 is a similar view taken on the line 5—5 of Fig. 3.

As shown, the weigh-beam is pivotally 50 supported upon a beam stand 1 attached to the upper surface of a beam shelf (not

shown), a trig stand 2 being also supported on said shelf. The stand 2 carries a trig 3 for limiting the movement, and also for locking in an immovable position, the tip of the beam. To the rear of the stand 1, the beam is provided with a pivotally mounted loop 4, that is connected to the lever system of the scale in the usual manner.

The weigh-beam includes a main bar 5 on which is mounted, in a manner to be hereinafter more fully described, a poise 6, and a secondary bar 7, which is suspended beneath the main bar 5, and carries a pair of poises 8 and 9. The main bar 5 is provided with notches 10 on its bottom which are engaged by a pawl (not shown) that is actuated by a lever 11, pivoted in the poise 6, while the secondary bar 7 has notches 12 formed on its top for retaining in position 70 the poise 8 in the usual manner. Carried by the poise 6 and positioned above the main bar 5 of the beam, is another bar 13 on which is slidably mounted a poise 14.

Each of the poises are rectangular in outline and they are each provided with a relatively large central opening 15 through which the scale graduations can be easily read, a vertically disposed, tapered indicator 16 being provided for pointing to the scale 80 markings. By preference the openings 15 are made wide enough to permit the numbered graduations to be visible without the necessity of shifting any of the poises after they have been correctly set in position.

In use, the poise 6 is the main poise, and the indicating point 16 thereof is adapted to register with scale graduations 17, formed on the bar 5. These graduations can be spaced to indicate divisions of 100 pounds 90 each. On the bar 13 graduations 18 can be formed, and such graduations can be numbered from 0 to 100. Thus, by setting the poise 6 to the next highest 100 pound division and then shifting the poise 14 to obtain proper balance of the beam, by adding the fractional weight indicated by such poise to the larger weight indicated by the poise 6, the total weight can be obtained.

The purpose of the secondary bar 7 and its two poises 8 and 9 is to enable the reading of tare weight, therefore the portion of

this bar on which is mounted the poise 8 and which portion also has formed thereon the notches 12, is provided with scale graduations 19 indicating divisions of 100 pounds each, while the portion of the bar on which slides the poise 9 is graduated, as at 20, into divisions that can be numbered from 0 to 100. The poises 8 and 9 are used in a manner similar to that described for the poises carried on the main portion of the beam, and therefore a detailed explanation of their function is not deemed necessary.

For sake of clearness, the minute scale graduations on the bars 7 and 13 have been omitted from the drawings, only the lines indicating the points 0, 20, 40, 60, 80 and 100, being shown.

If so desired the scale graduations 17 can be marked on strips 21 set into recesses formed on the faces of the beam, as clearly shown by Figures 4 and 5.

The upper surface of the bar 5 is in the nature of a track, consisting of two spaced parallel portions 22, which are arranged along the marginal edges of the beam, and a flat longitudinal rib 23 extending above, and positioned between, the parallel track portions.

As the poise 6 is relatively heavy, it is desirable that it be supported from the beam by anti-friction means. In the present instance I have chosen to suspend the poise by rollers 24 and 25. By preference the poise 6 is composed of similarly formed half sections which are suitably secured together by screws. In Figure 3, I have shown the inner face view of one of the poise sections, and the screws used to fasten the parts together are threaded into the openings 26 indicated in such view.

Formed in the poise is a central longitudinal chamber 27 which surrounds the beam. The rollers 24 and 25 are mounted in each end of the poise above the chamber 27. The roller 24 is adapted to contact with the track portion 22 and therefore it is provided with a pair of spaced flanges 28 which straddle the rib 23. On the other hand, the roller 25 is designed to support the poise from the rib 23 of the track, and therefore it is formed with a central concaved bearing portion 29, and also has a pair of spaced flanges 30, which are lesser in diameter than the flanges 28 of the roller 24.

Each of the rollers 24 and 25 are provided with trunnions 31 that are journaled in openings 32 formed in the side walls of the poise. In manufacturing roller 24, the central portion thereof between the flanges 28, can be made of substantially the same diameter as the trunnions 31, while in the manufacture of the roller 25, the central portion 29 thereof should be made somewhat greater in diameter than the trunnions. As the flanges 30 of the roller 25

are smaller in diameter than the flanges on the roller 24, such flanges 30 will not contact with the track 22 during movement of the poise along the beam, as will be readily understood.

The mounting of the poise 6 on the beam is such that the poise will be suspended from three points on the beam, two of the points being afforded at one end by the flanges of the roller 24, and the other point being at the opposite end of the poise by the central portion of the roller 25.

This arrangement of rollers provides means for preventing rocking across the corners of the poise which occurs when a four-point suspension is used. The means for suspending the poise in the manner above set forth permits the poise to readily move over the beam track and always take a correct position irrespective of slight irregularities in the track surface or roller bearings.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention, which, as a matter of language, might be said to fall therebetween.

Having thus described my invention, what I claim is:

1. A weigh-beam having a longitudinally extending track provided with an upstanding rib, and a poise suspended from said beam by a pair of flanged rollers so formed as to afford a three-point contact with the track, one point of contact being with said rib.

2. A poise for weigh-beams having a pair of flanged suspension rollers mounted therein for movement over a beam track with an upstanding centrally disposed rib, whereby the poise will be suspended from three points on said beam.

3. A weigh-beam having a longitudinally extending rib on the upper side thereof, a poise mounted on the said beam, and a pair of flanged supporting rollers carried by the said poise, one of said rollers straddling the said rib.

4. A poise for weigh-beams having a pair of suspension rollers mounted therein for movement over a beam track with an upstanding centrally disposed rib, one of said rollers having flanges engaging the track on each side of the rib, while the other

roller engages said rib, thereby supporting the poise at three points.

5. A weigh-beam for scales having a longitudinally extending rib on the upper side thereof, a poise mounted on the said beam, and a pair of supporting rollers carried by the said poise, one of the said rollers strad-

dling the said rib and the other roller riding on the rib, whereby said poise is supported by three points.

10 In testimony whereof, I hereunto sign my name.

ALFRED C. HOWARD.
